UNITED STATES PATENT OFFICE

IRVING E. VAN AUKEN, OF TWIN FALLS, IDAHO

OIL BURNER

Application filed September 18, 1930. Serial No. 482,360.

This invention relates to improvements in liquid fuel burners and pertains particularly to an improved type of oil burner.

The primary object of the present invention is to provide an oil burner for the burning of heavy oils, wherein the oil is vaporized and wherein water is vaporized, the vapor of the oil and the water being so mixed and burned that the formation of soot is greatly reduced and the creation of smell which usually results from the burning of crude oils, is prevented.

Another object of the invention is to provide an oil burner having an improved and novel type of burner unit onto which the oil is discharged and transformed into a vapor, and through which water vapor is passed for mixture with the oil vapor, the burner being rotatable so that new oil receiving surfaces may be brought into use as necessary.

A still further object of the invention is to provide an oil burner having a rotatable unit upon which oil is discharged during the operation of the burner for transformation into vapor, which is so arranged that only a portion of the area thereof will be in use during the operation of the burner. By rotation of the unit new areas thereof may be arranged to receive oil while the areas which have already been used are being freed of any deposit which may have formed thereon, the shifting or rotation of the unit being effected without removing the unit from the stove or heater in which it is mounted.

Other objects and advantages of the invention will become apparent as the description of the same proceeds and the invention will be best understood from a consideration of the following detailed description taken in connection with the accompanying drawings forming part of this specification, with the understanding, however, that the invention is not confined to any strict conformity with the showing of the drawings but may be changed or modified so long as such changes or modifications mark no material departure from the salient features of the invention as expressed in the appended claims.

In the drawings:
50 Figure 1 is a view in front elevation of

the upper portion of a stove of the wood or coal range type showing the application thereto of the oil burner embodying the present invention.

Figure 2 is a vertical transverse section through the stove fire box showing the oil burning unit embodying the present invention partly in side elevation and partly in section.

Figure 3 is a sectional view taken on the line 3—3 of Figure 2.

Figure 4 is a view showing the application of the oil burner embodying the present invention to a portable stove.

Referring more particularly to the drawings wherein like numerals of reference indicate corresponding parts throughout the several views, the numeral 1 indicates generally a stove of the coal or wood range type wherein the top 2 is provided with a number of removable lids 3, certain of these lids closing openings through which access is had to the stove fire box 4.

For the installation of the oil burner embodying the present invention one of the lids 3 which covers an opening to the fire box of the stove is provided with a pair of apertures through which pipes, hereinafter specifically designated, are run to the burner unit of the device as shown in Figure 2.

The burner comprises an oil feed pipe 5 which has one end directed upwardly and terminating in a receiver 6 here shown as in the form of a funnel while the other end has an inclined portion which is coupled with the laterally directed arm of a three-way coupling 7. The other two arms of the coupling 7 are inclined slightly from the vertical as shown and the lower one is connected through the medium of a nipple 8 which passes through one of the apertures in the plate 3, with one of the aligned arms of a second three-way coupling 9.

The upper end of the coupling 7 has a plate 10 thereon through which passes a rod 11, this rod extending downwardly through and beyond the lower end of the coupling 9 and terminating in a point 12 as shown. The upper end of the rod 11 has a head 13 and

disposed between this head and the plate 10 is a spring 14.

From the description thus far given it will be seen that the couplings 7 and 9 are so arranged and supported by the pipe 5 as to extend in a line which is inclined or tilted slightly from the vertical so that the other elements, about to be described, which are carried by the lower one of the couplings 9, 10 will be arranged at an angle or tilted in the fire box.

Disposed within the stove fire box 4 is a pipe 15 in which is interposed a three-way coupling 16. This pipe at one end is connected by the several unions and pipe sections which form a supporting arm indicated generally by the numeral 17, with the lateral arm of the coupling 9, while the other end has secured thereto one arm of a right angle union or coupling 18, the other arm of which is directed upwardly as shown.

The coupling 16 has connected thereto a water conducting pipe 19 which extends upwardly through the other aperture of the plate 3 and joins a pipe 20 in which a U-bend 21 is formed to provide a trap. The other end of this pipe 20 is connected with an upwardly directed pipe section 22 which terminates at its upper end in a receiver or funnel 23.

Within the fire box 4 there is a burner plate which is indicated generally by the numeral 24. This burner plate is preferably of circular configuration and has an upper standing rim or flange 25 formed about its edge, the central portion being provided with a threaded opening 26 in which is threadably engaged one end of a short pipe or tube 27, the other end of which is extended into the upwardly directed end of the coupling 18 in the manner shown so that the burner plate will be supported upon this coupling and will be prevented from slipping or being accidentally moved therefrom by this tube.

The tube 27 is of materially less over-all diameter than the interior diameter of the end of the coupling into which it extends and in order to maintain the tube centered the inner wall of the upwardly directed portion of the coupling 18 is provided with several lugs 28 against which the outer surface of the tube abuts. The central part of the plate 24 is provided with an annular wall 29 which surrounds and is concentric with the opening 26 through which the tube 27 extends so that the burner plate is divided into a central cup 30 and a surrounding relatively broad channel 31.

As shown in Figure 2 the rod 11 reaches down to the burner plate 24 so that the lower end or point 12 thereof may be brought into contact with the surface of the annular portion 31. This rod 11 fits loosely in the couplings 7 and 9 and the nipple 8 through

which it passes so that considerable lateral motion is permitted to facilitate the rotation of the plate 24 thereby. By pressing downwardly upon the head 13 of the rod to bring the point thereof into contact with the burner plate and then tilting or oscillating the rod the burner plate may be rotated slightly, the pipe or tube 27 acting as a pivot therefor.

Any suitable means may be employed for supplying water and oil to the respective pipes 20 and 5 but in the drawings there has been shown for convenience a pair of receptacles, the oil receptacle being indicated by the numeral 32 while the water receptacle 89 is indicated by the numeral 33. Each of these receptacles is provided with a faucet 34. The faucet upon the oil tank 32 discharges into the receiver 6 upon the end of the oil pipe 5 while the faucet on the tank 33 discharges into the receiver 23 upon the water pipe 20.

In operation the faucets 34 are regulated to drip the oil and water into their respective receiving funnels, some of the oil having been run onto the burner plate 24 and ignited before the water is turned on. Due to the angle at which the parts are disposed in the fire box it will be seen that the burner plate is also supported at an inclination, the lowest point thereof being substantially diametrically opposite the area directly behind the point where oil falls thereon from the discharge arm of the coupling 9.

After a sufficient quantity of oil has dripped from the discharge arm of the coupling 9 onto the annular portion 31 of the burner plate to flow to the opposite or lowest point thereof so that substantially half of the area of the annular portion is covered with oil, the oil on the plate is ignited and the flame thereof is, of course, continually fed by the oil flowing from the discharge pipe. After the oil has burned a sufficient length of time to thoroughly heat the surrounding elements the water is then permitted to flow slowly into the pipe 15 where it will be converted into steam due to the heated condition of this pipe and this steam will pass upwardly through the tube 27 into the cup 30. As the pipe 27 and, of course, the plate 24 will be in a highly heated state the steam generated in the pipe 15 will be superheated as it comes into contact with these parts and will enter the cup 30 in a superheated dry condition to mix with the flame of the burning oil and the addition of the oxygen content of this super-heated steam to the burning oil will cause the oil to be practically completely consumed.

In the use of this oil burner a slight amount of carbon will be deposited on the surface of the plate 24 though there will be less carbon deposited than there is deposited by burners of the usual type. When the surface of a sec-

tion of the burner plate receives an amount of carbon which would interfere with the proper burning of the oil the rod 11 may be depressed until the point is brought into contact with the surface of the plate and then oscillated so as to use the lower end thereof for turning the plate on the coupling 18. This operation is carried on until the plate has been given a half turn so that an unused portion of the channel will be brought into position to receive oil from the oil discharging line. The carbon remaining on the used half of the plate will be burned off during the use of the new section which has been turned into position to receive a supply of oil. The necessary air draft for the operation of the burner is provided through the aperture 41 formed through the plate 3 from which the burner structure is suspended.

20 In Figure 4 there is shown the application of the burner structure embodying the present invention to a portable heating stove, the stove being indicated generally by the numeral 35. The top of the stove 35 is provided 25 with a bar 36 which is suitably secured thereto, each end of which bar is turned upwardly and inwardly to form the supporting bracket arm 37. Upon one of these arms the water tank 38 is mounted, while upon the other the oil tank 39 is mounted and each of these tanks 30 has a faucet 40 like the tanks 32 and 33, each of which discharges into a receiving funnel 39 located therebeneath. It is, of course, understood that the structure within the stove 35 is a duplication of the structure shown in Figure 2, therefore, details of the same have not been shown.

Having thus described my invention, what I claim is:

40 1. An oil burner, comprising a burner plate designed to be disposed within a fire box, said plate having its top surface formed to provide an oil receiving channel, means for supporting the plate for rotation in the fire box, means for conducting oil to said plate for discharge into said channel, means for conducting water in close proximity to said plate to be converted into steam by the heat of the plate, means for passing the steam formed in said conducting means through the heated plate to super-heat and discharge the same over the top of the plate for mixture with the flame of burning oil in said channel, said plate being inclined slightly to cause 45 the oil to flow over a part thereof, and means for turning the plate.

2. An oil burner, comprising a burner plate having the top surface thereof formed to provide an oil receiving channel, said plate being designed to be positioned in a fire box, means for supporting the burner plate for rotation in the fire box, a water pipe line leading to and opening upwardly through said plate, an oil conducting pipe leading to and terminating over the top of said plate for

discharging oil into said channel, and means for supplying a regulated quantity of oil and water to the said oil and water pipes, said water pipe being arranged to conduct the water therein into close proximity with the plate to effect the conversion of the water to steam before discharge upwardly through said plate.

3. An oil burner, comprising a burner plate having the top surface thereof formed to provide an oil receiving channel, said plate being designed to be positioned in a fire box, means for supporting the burner plate for rotation in the fire box, a water pipe line leading to and opening upwardly through said plate, an oil conducting pipe leading to and terminating over the top of said plate for discharging oil into said channel, means for supplying a regulated quantity of oil and water to the said oil and water pipes, said water pipe being arranged to conduct the water therein into close proximity with the plate to effect the conversion of the water to steam before discharge upwardly through said plate, said plate being inclined to cause the oil thereon to spread over a part only of the surface of the channel, and means for rotating the plate to bring a selected portion into position beneath the oil discharge pipe, for use.

4. An oil burner of the character described, comprising a pipe section terminating at one end in an upwardly opening angle coupling, a circular burner plate having an oil receiving recess in one face thereof and further having a central recess or cup in the same face, a tubular connection extending at one end through the plate and opening into said cup and having its other end extended into the upwardly opening end of said coupling to 105 rotatably support the plate on the coupling, a pipe connected with said pipe section for conducting water thereto, and an oil supply pipe for said burner terminating in a portion overlying and discharging into the 110 recess of said plate to discharge oil thereinto.

5. An oil burner of the character described, comprising a pipe section terminating at one end in an upwardly opening angle coupling, 115 a circular burner plate having an oil receiving recess in one face thereof and further having a central recess or cup in the same face, a tubular connection extending at one end through the plate and opening into said cup and having its other end extended into the upwardly opening end of said coupling to rotatably support the plate on the coupling, a pipe connected with said pipe section for conducting water thereto, an oil 125 supply pipe for said burner terminating in a portion overlying and discharging into the recess of said plate to discharge oil thereinto, and a reciprocable member extended through the terminal portion of the oil pipe 130

and adapted to engage the plate to facilitate the rotation thereof.

6. The combination with a stove having a lid removable from over a fire box, of a pipe extending through said lid, a burner disk having a recessed top surface, a supporting element connected to said pipe and including a pipe extending substantially at right angles to the first pipe and terminating in an upturned discharge end, a short tubular body having one end extended through the central portion of said disk and having its other end rotatably mounted in the upturned end of said last pipe, a pipe coupling with said last pipe for conducting water thereto, said water conducting pipe having a trap therein, and an oil pipe connected with said first pipe for discharging oil downwardly therethrough into the recess of said plate.
10. 7. The combination with a stove having a lid removable from over a fire box, of a pipe extending through said lid, a burner disk having a recessed top surface, a supporting element connected to said pipe and including a pipe extending substantially at right angles to the first pipe and terminating in an upturned discharge end, a short tubular body having one end extended through the central portion of said disk and having its other end rotatably mounted in the upturned end of said last pipe, a pipe coupled with said last pipe for conducting water thereto, said water conducting pipe having a trap therein, an oil pipe connected with said first pipe for discharging oil downwardly therethrough into the recess of said plate, and a vertically reciprocable member extending through said first pipe and shiftable therein for maintaining the same open and adapted to engage the plate to facilitate the moving thereof.

8. The combination with a transportable stove of a water and hydrocarbon burner including a burner plate adapted to receive the hydrocarbon for combustion thereon, a supporting structure upon the stove including a pair of brackets, a receptacle upon each of said brackets one being provided to contain oil and the other to contain water, a receiver adjacent each receptacle, a valve for controlling the discharge of fluid from each receptacle into the adjacent receiver, means for conducting oil from one receiver to and discharging it upon the burner plate, means for conducting water from the other receiver to a point adjacent the burner plate, and means for converting the water to super-heated steam at the burner plate and for discharging the steam upwardly through the plate for mixture with the flame of the oil burning thereon.

9. The combination with a stove having a removable fire box lid, of a pipe member extending through and secured in said lid, an arm carried by said pipe member and having an upturned tubular terminal portion, a

burner plate rotatably mounted upon said upturned portion and having a central passage therethrough in communication with the interior of the same, means for conducting water to the interior of the terminal portion of said arm, and means for discharging oil into said pipe, said pipe being disposed to discharge the oil thereinto onto said plate.

10. A fuel oil burner unit adapted to be suspended in a combustion chamber, comprising a substantially vertically disposed tubular oil conductor, means for introducing oil into the upper end of said conductor, means carried by the conductor for mounting it in upright position with its lower end in the combustion chamber, a bracket carried by said oil conductor and having an upturned tubular terminal portion, a fuel combustion plate rotatably mounted upon the upturned terminal portion of the bracket and having a central passage therethrough in communication with the interior of the said terminal portion, means for introducing water into the tubular terminal portion of the bracket, said plate being disposed at a slight inclination from the horizontal, and means for effecting the rotation of the plate.

In testimony whereof I hereunto affix my signature.

IRA E. VAN AUKEN.
